UNITED STATES PATENT OFFICE.

BROR J. LINDGREN, OF BUFFALO, NEW YORK, ASSIGNOR TO NIAGARA MACHINE & TOOL WORKS, OF BUFFALO, NEW YORK, A CORPORATION OF NEW YORK.

SHEET-METAL-BENDING MACHINE

Application filed December 5, 1921. Serial No. 519,834.

To all whom it may concern:

Be it known that I, BROR J. LINDGREN, a citizen of the United States, residing in Buffalo, in the county of Erie and State of New York, have invented new and useful Improvements in Sheet-Metal-Bending Machines, of which the following is a specification.

This invention relates to a machine for bending a sheet of metal into tubular form, and more particularly to a machine of this character which is adapted to bend into tubular form a sheet which has been previously corrugated so that the tube resulting therefrom will have the corrugations extending circumferentially around the same and may be subsequently converted into a stove pipe elbow.

It is the object of this invention to produce a machine whereby such bending may be accomplished effectively, expeditiously and economically and by means which can be easily operated with a minimum expenditure of power and without liability of derangement, as well as permitting of ready adjustment for producing pipes from sheet metal of various diameters and lengths.

In the accompanying drawings:

Figure 1 is a sectional elevation of a satisfactory embodiment of my invention, the section being taken on line 1—1, Fig. 2. Figure 2 is a top plan view of the same. Figure 3 is a fragmentary vertical section, taken on line 3—3, Fig. 1. Figure 4 is a side elevation of the machine. Figure 5 is a vertical longitudinal section taken on line 5—5, Fig. 1. Figure 6 is a fragmentary vertical section taken on line 6—6, Fig. 13. Figures 7 and 8 are fragmentary sections taken on the correspondingly numbered lines in Fig. 6. Figure 9 is a vertical longitudinal section of the machine taken on line 9—9, Fig. 1. Figures 10 and 11 are fragmentary vertical longitudinal sections, on an enlarged scale, of the feeding and turning rollers and adjacent parts and showing the manner of operating the same for producing a preliminary bend in the front end of the sheet of metal which is to be bent and the subsequent bending of the same into tubular form. Figure 12 is a fragmentary

longitudinal section of the opposing portions of the feeding rollers showing the manner in which they co-operate for gripping a corrugated sheet of metal between the same. Figure 13 is a fragmentary vertical transverse section, taken on line 13—13, Fig. 2, and showing the parts in the position which they occupy when removing a finished sheet metal tube therefrom. Figure 14 is a fragmentary vertical section, taken on line 14—14, Fig. 4. Figure 15 is a fragmentary longitudinal section taken on line 15—15, Fig. 1. Figures 16, 17, 18 and 19 are fragmentary sections taken on the correspondingly numbered lines in Fig. 15. Figure 20 is a perspective view of a completed corrugated sheet metal tube which is produced by my improved machine and which may be converted into a stove pipe elbow. Figure 21 is a fragmentary side elevation of a machine showing a modified form of the means for adjusting the turning roller relative to the feed rollers of the machine. Figure 22 is a front elevation of the same, partly in section. Figure 23 is a fragmentary vertical section, taken on line 23—23, Fig. 22. Figure 24 is a fragmentary vertical section taken on line 24—24, Fig. 21.

Similar characters of reference refer to like parts throughout the several views.

30 represents the main frame of the machine which may be of any suitable construction to support the various working parts of the machine. On the upper rear part of the main frame is arranged a horizontal feed table or support 31, upon which the sheet of metal 32 which is to be bent into tubular form, is supported preparatory to operating thereon. As shown in Figs. 1 and 9—13, this sheet has been previously provided with a plurality of longitudinal corrugations 33 and at its rear edge with a lateral off set 34 and when this machine has completed its operation upon this sheet, the same will be of tubular form with the corrugations extending circumferentially around the same and the off set rear edge thereof overlapping the outer side 100 of the front edge of the sheet, as shown in Fig. 20, ready to be bent into elbow shape

for use as a stove pipe elbow or for other purposes.

When placing this sheet of metal upon the feed table the same is received with its front edge between an upper and a lower feeding roller which are adapted to feed the sheet forwardly. Its front edge is adapted to rest upon a turning member which operates to turn the sheet to one side of the path or direction of the movement at which it reaches the front side of the feed rollers, and the rear part of the sheet is confined in its proper place on the feed table by means of gages which cause a sheet to be properly presented to the feeding rollers and to be guided while being fed forwardly during the operation of converting the same into a tube.

The preferred means for thus gaging the sheet while the same rests upon the feed table comprise a rear gage 35 preferably in the form of a bar, adapted to engage with the rear edge of the sheet of metal and capable of being adjusted lengthwise on the feed table for adapting the machine to sheets of different lengths for forming tubes of different diameters, this adjustment consisting preferably of adjusting bolts 36 arranged at opposite ends of the rear gage bar 35 and adapted to enter one or another of the two longitudinal rows of openings 37 arranged adjacent to opposite longitudinal edges of the table 31. On the left hand side of the feed table is arranged a left hand gage 38 preferably in the form of a bar which is adapted to engage with the left hand edge of the sheet of metal which is to be bent and which is capable of transverse adjustment on the feed table for adapting the machine to sheets of metal of various widths for producing sheet metal tubes of corresponding length, this adjustment being preferably effected by means of adjusting bolts 39 arranged at opposite ends of the gage bar 38 and adapted to engage with one or another of two transverse rows of openings 40, formed in the feed table 31 adjacent to its left hand edge.

The right hand edge of the sheet of metal is adapted to engage with a gage 41 arranged adjacent to the front part of the right hand longitudinal edge of the feed table and capable of transverse adjustment thereon for adapting the same to sheets of metal of different widths for producing tubes of different lengths, this adjustment being effected by a pair of adjusting bolts 42 arranged on this gage and adapted to engage with one or another pair of openings 43 arranged in transverse rows on the front part of the table adjacent to the right hand edge of the same.

In order to continue the gaging operation of the sheet of metal as the same is converted into a tube and also guide the same

during this operation, so that its ends will come out even, a bending end gage 44 is provided which extends forwardly and upwardly from the left hand gage bar 38, this bending gage having its face flush with the respective side bar 38 and provided with a vertical slot 45 whereby the same is capable of straddling the upper feed roller. This bending end gage is preferably secured to the left hand side gage bar 38 by means of bolts 46, as shown in Fig. 2, or otherwise, so that these members may be adjusted simultaneously transversely of the machine for adapting the same for the formation of sheet metal tubes of varying length.

Generally speaking, the upper and lower feeding rollers are provided with circumferential corrugations, the salient parts or ribs of the corrugations of one roller being opposite the receding parts of the grooves of the corrugations of the other feed roller and the corrugations of the sheet metal being received between these corrugations, so that these corrugations of the feed rollers register with those of the sheet of metal and produce a grip on opposite sides of the latter for causing the sheet of metal to be fed forwardly from the feed table and against the turning member for bending the sheet into tubular form during the normal operation of the machine. In order to enable the corrugations of the feeding rollers to engage with the corrugated parts of the sheet of metal and ensure a firm grip thereon for positively feeding the same forwardly without however distorting or changing the formation of the corrugations of the sheet other than converting the same into tubular form, the corrugations of one of these feeding rollers are made comparatively deep and those on the other feeding roller are made comparatively shallow, so that when the corrugations of the sheets of metal are gripped by the corrugations of the feeding rollers, the summit of the deep corrugation of one of the feeding rollers and the valley of one of the shallow corrugations of the other feed roller will engage with opposite sides of one of the corrugations of the sheet of metal toward one side of the latter, while the summit of each of the shallow corrugations on one of the feeding rollers and the corresponding valley of a deep corrugation on the other roller will be spaced apart from opposite sides of the corrugation of the sheet toward the other side of the same, as shown in Fig. 12. By this means the sheet of metal will only be gripped on its opposite sides at the alternate corrugations thereof, instead of over its entire surface, whereby only so much frictional engagement of the feeding rollers on this sheet is effected as is required to positively feed the sheet forwardly without however changing the cross sectional

form of the corrugations in the sheet during such feeding operation. As shown in Fig. 12, the deep corrugations 47 are formed on the upper feeding roller 48 and the shallow corrugations 49 are formed on the lower feeding roller 50, but if desired this organization may be reversed.

When a machine of this character is used continuously for making corrugated

- 10 tubes of the same length, all of the corrugations may be formed permanently or integrally on the body of each feeding roller, but when the same machine is to be used for making circumferentially corrugated
- 15 sheet metal tubes of different lengths, means are provided whereby the corrugated area of these feeding rollers may be shortened or lengthened to suit the particular length of tube which is to be manufactured. This
- 20 is preferably effected by providing the bodies of these feeding rollers, which in effect constitute the shafts of the same, with a sufficient number of permanent integral corrugations 51, 52 for operating upon a
- 25 minimum number of corrugations which are likely to be used in the formation of a corrugated tubular sheet of metal of minimum length and in addition thereto a plurality of corrugations 53, 54 are remov-
- 30 ably mounted on the shafts of these feeding rollers, so as to permit of increasing the corrugations on these rollers more or less, as required, to suit a correspondingly increased corrugated area on a sheet of metal which
- 35 is to be bent into a tube. Such removable corrugations are mounted on collars 55, 56 which are slipped on reduced parts 57, 58 of the upper and lower feed roller shafts adjacent to the permanent corrugations there-
- 40 on, so that when these removable collars are assembled with the shafts the corrugations on each of these rollers will form a continuous and regular series from one end of the row of corrugations to the other, as
- 45 best shown in Fig. 13. Adjacent to the corresponding left ends of the series of permanent corrugations of the feeding rollers, the latter are provided with cylindrical faces 59 and 60 which co-operate to
- 50 grip between them the uncorrugated edge portion 61 at one of the longitudinal edges of the sheet of metal which forms one end of the tube, as shown in Figs. 13 and 20, and adjacent to the right end of the re-
- 55 movable corrugations, cylindrical gripping sleeves 62, 63 are mounted upon the reduced parts of these rollers which gripping sleeves receive between them the uncorrugated portion at the opposite longitudinal edge of the
- 60 sheet of metal which produces the uncorrugated edge portion 64 at the opposite end of the tube, as shown in the same figures. These gripping sleeves and the collars carrying the removable corrugations of the feeding
- 65 rollers are pressed inwardly for the purpose

of holding the same in their proper position on the shafts of the upper and lower feeding rollers by means of bearing sleeves 64, 65 arranged on the adjacent ends of these rollers and engaged by clamping screw nuts 66, 67 arranged at the respective ends of the shafts of these rollers and engaging the outer ends of the bearing sleeves, as best shown in Figs. 13 and 14.

The lower feeding roller is arranged immediately in front of the front edge of the feed table with its upper surface substantially in line therewith and the same is journaled at that end thereof having the permanent gripping surface 60 in a bearing 68 arranged at the upper end of a standard 69 rising from the adjacent part of the main frame while the bearing sleeve 65 at the other end of this shaft is journaled in a bearing 70 which is preferably made vertically adjustable so as to permit of bringing the same in the proper position relative to the upper feeding roller during the normal operative position of the parts. For this purpose the bearing 70 is guided in a vertical way 71 formed in the upper part of a standard 72 rising from the main frame on that side thereof opposite to the standard 69 and a vertical adjusting screw 73 is arranged in a threaded opening in the standard 72 and engaged at its upper end with the underside of the bearing 70 so that by turning the screw 73 in one direction or the other the lower feeding roller may be tilted up or down at its right hand end for the purpose of bringing the same into proper alignment relative to the upper feeding roller for producing the proper gripping effect of the feeding rollers on the sheet of metal which is to be converted into a tube.

When the sheet of metal has been converted into a tube, the same surrounds the upper feeding roller and its lower part is gripped between the upper and lower feeding rollers. In order therefore to permit of removing the finished tube from the machine, the upper feeding roller is raised preferably at one end thereof, and the raised end is detached from its support, as shown in Fig. 13, leaving the space around the raised end of the upper feeding roller unobstructed, so that the finished sheet metal tube may be withdrawn lengthwise therefrom, the position of this tube while being thus removed being indicated by dotted lines in this figure. A practical way for thus operating the upper feeding roller consists in journaling that end of the same opposite to its bearing sleeve 64 in a vertically swinging bearing 74 which latter is formed on a vertically swinging yoke 75 having horizontal longitudinal trunnions or pivots 76 on its opposite sides which are journaled in bearings 77 on the upper part of the standard 69, as best shown in Fig. 3.

Any suitable means may be provided for turning these feeding rollers so that their cooperating opposing surfaces which grip the sheet of metal move forwardly, this being accomplished in the present instance by means of a driving shaft 78 provided with a driving pinion 79 meshing with a driven gear wheel 80 on the shaft 50 of the lower feeding roller and a pair of co-operating gear pinions 81, 82 of like diameter secured respectively to those ends of the lower and upper feeding rollers adjacent to the bearings 68 and 74 of the same. The relative arrangement of the gear pinions 81 and 82, is preferably such that upon lowering the right or free hand end of the upper feeding roller, the gear pinion 82 will be in mesh with the lower gear pinion 81 and cause the two feeding rollers to run in unison and upon raising the right hand end of the upper feeding roller, the upper gear pinion 82 will remain in mesh with the lower gear pinion 81. The rotation of the feeding rollers is stopped while the operator is removing the finished sheet metal tube therefrom.

Power may be supplied to the driving shaft 78 in various ways, for instance, by means of a power belt passing around a power pulley 83, mounted on the driving shaft 78 and adapted to be connected therewith or disconnected therefrom by means of a clutch 84 which latter is coupled or uncoupled by means of a clutch lever 85 pivoted on the adjacent part of the main frame and having its upper arm connected with the clutch 84, as best shown in Figs. 1 and 2.

For the purpose of holding the right hand end of the upper feeding roller reliably in position during the operation of the machine, but permitting the same to be released and raised to permit of stripping the finished tube therefrom, the following means are provided:

86 and 87 represent the lower and upper sections of a divided bearing block which receive between them the bearing sleeve 64 of the upper feeding roller. The lower section 86 is preferably formed integrally with the standard 72 at the upper end thereof and the upper section 87 is preferably so mounted that the same is movable relatively to the lower bearing block section so as to permit of engaging this upper section with or disengaging the same from the upper side of the bearing sleeve 64. For this purpose the upper side of the upper bearing block section 87 is provided with an eccentric bearing loop or strap 88 which receives an eccentric 89. This eccentric together with its loop 88 is arranged between the upper parts of the two yoke bars 90, 91 which are arranged on opposite sides of the standard 72 and which are connected at their upper

ends by means of a bolt 92 while their lower ends are pivotally connected by means of a horizontal longitudinal pin 93 with the lower part of the standard 72 so that in effect these bars form a laterally swinging yoke which permits of carrying the upper bearing block section inwardly over the top of the bearing sleeve 64 preparatory to operating the machine, as best shown in Figs. 1, 2, 14 and 15 or laterally to one side 76 of the bearing sleeve 64 to permit the upper feeding roller to be raised, as shown in Fig. 13.

When the upper bearing block section 87 is over the bearing sleeve 64 this bearing block section is pressed downwardly so as to confine the bearing sleeve 64 between the same and the lower bearing block 86 by turning the eccentric 89 in the proper direction for which purpose a horizontal longitudinal shaft 94 is provided which carries the eccentric 89 and is journaled in the upper part of the yoke arms 90, 91 and is provided adjacent to the outer side of the yoke arm 90 with the crank arm 95 for turning the shaft 94 and the eccentric 89 connected therewith. Means are provided for holding the eccentric 89 yieldingly in such a position in which the upper bearing block is held against the upper side of the bearing sleeve 64 or released therefrom to permit of swinging the same laterally therefrom, the preferred means for this purpose shown in the drawings consisting in providing the inner side of the hub of the crank arm 95 with a retaining disk 96 having two recesses 97, 98 on different parts thereof circumferentially of the axis of the shaft 94 and a spring pressed catch 99 arranged on the adjacent part of the yoke bar 90 and adapted to engage with one or the other of the recesses 97 or 98 for the purpose of holding the upper bearing block either in its operative or its loosened position.

For the purpose of limiting the upward and inward motion of the yoke 90, 91 and also retaining the same firmly in place when the same and the parts mounted thereon are in their operative position, retaining means may be provided which may be variously constructed, but which in the present instance consist in forming inclined surfaces 100 on the inner sides of the upper parts of the yoke bars 90, 91 and engaging the same with correspondingly inclined faces 101 on the upper parts of the outer sides of the standard 72, one pair of these cooperating inclined faces being shown in Fig. 16. By this means a wedging engagement of the yoke 90, 91 with the standard 72 is produced upon swinging this yoke upwardly into its operative position, whereby these parts are firmly held against fore and aft motion relative to each other. The inward and upward motion of the yoke 90, 91 in this di-

rection is limited by engagement of the bar 90 of this yoke with the stop 102 on the adjacent part of the standard 72, as shown in Figs. 1, 17 and 19. The yoke is yieldingly held in its operative position by means of a spring pressed catch 103 arranged on the standard 72 engaging with a recess 104 on the inner side of the adjacent yoke bar 90, as shown in Figs. 15, 17 and 19. The shaft 94 is preferably extended rearwardly a sufficient distance beyond the crank 95 so as to serve as a handle 105 whereby the yoke may be manipulated by one hand for swinging the same upwardly or downwardly into its operative or inoperative position, while the other hand is engaged in manipulating the crank 95 for tightening or loosening the upper bearing block 87.

It is preferable to automatically raise the upper feeding roller from the lower feeding roller at the same time that the yoke 90, 91 and the parts mounted thereon are moved into their inoperative and operative positions and thus avoid the necessity of separate manipulations for this purpose and expediting the out put of the machine and increasing the capacity of the machine accordingly. For this purpose the yoke 75 is provided with a downwardly projecting shifting rock arm 106 which is connected by means of a shifting bar or rod 107 with the front bar 91 of the clamping yoke above the axis of the pivot pin 93 thereof, whereby an outward and downward movement of the yoke 90, 91 will cause the upper feeding roller to be lifted, as shown in Fig. 13, while an upward and inward movement of the clamping yoke will cause the upper feeding roller to be lowered, as shown in Fig. 1. In order, however, to permit the clamping yoke to first move laterally sufficient to carry its upper bearing block clear of the bearing sleeve 64 of the upper feeding roller before the latter begins its upward motion, a slack connection is provided in the shifting means which operatively connects the bearing yoke 75 of the upper feeding roller and the clamp yoke, which slack connection preferably consists of a pin 108 arranged in the lower end of the shifting arm 106 and working in a longitudinal slot 109 in the left hand end of the shifting rod 107. The formation of this pin and slot connection is such that when the clamping yoke 90, 91 is in its upper operative position, the pin 108 will be arranged at the right hand end of the slot 109, as shown in Fig. 1. If now the clamping yoke 90, 91 is swung outwardly and downwardly the same together with the shifting bar or rod 107 will move independently of the upper feeding roller until the upper bearing block 87 is clear of the bearing sleeve 64 and then the left hand end of the slot 109 will engage with the pin 108 so as to cause the shifting arm 106 to move

with the clamping yoke 90, 91 and cause the upper feeding roller to be lifted during the continued outward and downward movement of the clamping yoke. In like manner when the clamping yoke is raised and moved inwardly the same will move in unison with the upper feeding roller until the bearing sleeve 64 of the latter is resting upon the lower bearing block section 86 and thereafter the upward and inward motion of this clamping yoke will continue while the upper feeding roller is at rest and thus permit the upper bearing block section to be moved into its operative position and clamped against the upper side of the bearing sleeve 64.

The turning member which intercepts the advancing portion of the sheet of metal as the same issues from between the feeding rollers from the front side thereof is preferably constructed in the form of a roller 110 which is provided with a plurality of circumferential corrugations 111 corresponding to those of the feeding rollers, so as to register with the corrugations of the sheet of metal which is being operated upon, said turning roller being arranged horizontally and transversely in the path of the sheet of metal and causing the same to be bent or curled upwardly so that when the entire sheet has passed between the rollers, the front end of the sheet will lap over the off set rear end 34 of this sheet and form a complete cylinder or tube therewith, as indicated by dotted lines in Fig. 9. If the tube has been thus completed, it is immaterial whether the feeding rollers continue their engagement with the sheet or tube inasmuch as the tube will simply continue its turning movement between the feeding rollers under the rotary action of the latter and continue to roll in contact with the corrugations of the tube and also the overlapping portions thereof without producing any further effect.

In order to permit of varying the position of the turning roller in a vertical direction or perpendicular to the normal path of the sheet as the same issues from the feeding rollers and thus enable the longitudinal edges of the finished tube to overlap each other properly and also to adapt the machine for making tubes of different diameters the following means are provided.

112 represents a cross bar arranged below the turning member 110 and provided at its opposite ends with bearings 113 in which the opposite ends of the turning roller are journaled. 114 represents two upright curved guide arms each of which is guided in a curved way 115 secured to the adjacent part of the main frame, the curvature of these arms and guideways being such that the axes of these curves are approximately coincident with the axis of the lower feeding roller,

as shown in Fig. 6, so that upon sliding these 5 guide arms on these guide ways, the turning roller 110 will be moved toward or from the feeding rollers to suit tubes of different diameters. The upward movement of these 10 guide arms and the parts mounted thereon is preferably effected by means of an adjusting screw 116 working in lugs 117 on the front sides of these guide arms and bearing 15 against abutment lugs 118 on the adjacent part of the main frame while the downward movement of the same, after loosening the 20 adjusting screws 116, may be effected by downward hand pressure on the same. After 25 adjustment, each of these guide arms may be held in position by means of clamping screws 119 secured to each of the curved guides 115 and passing through curved slots 120 in the respective guide arm, as best shown in Figs. 20 6, 7 and 8.

If desired, the turning roller 110 may be raised and lowered relative to the feeding 25 rollers by the means which are shown in Figs. 21-24 and which are constructed as follows:

121 represents two vertically swinging 30 shifting arms which are arranged lengthwise in the front part of the machine below the feeding rollers and pivoted by means of pins 35 221 at the rear ends to the adjacent lower part of the frame while their front ends are connected by means of longitudinal pivot pins 122 with opposite ends of the cross bar 123 upon which the turning roller 110 is 40 journaled. 124 represents a horizontal operating shaft which is journaled transversely in suitable bearings on the front part of the main frame and provided near its opposite 45 ends with eccentrics 125.

40 Each of these eccentrics is surrounded by an eccentric strap 126 which is connected by a rod or pitman 127 with the shifting arm 121 on the corresponding side of the machine. Upon turning the shaft 124 in one 45 direction or the other the turning roller 110 will be raised and lowered, this turning movement being preferably effected by means of a crank arm 128 which is secured to one end of the shaft 124. The swinging 50 movement of the operating arm 128 is effected by means of a crank shaft 129 journaled in the upper end of the operating arm 128 and provided at one end with a gear pinion 130 which meshes with a gear segment 131 on the adjacent part of the main frame concentrically with the axis of the operating shaft 124 and a crank 132 connected with the outer end of the crank shaft 129. By this means a 55 turning movement of the crank arm 132 in either direction will cause the pinion 130 to roll upwardly or downwardly on the segment 131 and thereby shift the operating arm 121 and the parts associated therewith so as to raise or lower the turning roller 110

60 relatively to the feeding rollers. For the purpose of locking the turning roller in whatever position the same may be adjusted a locking device is provided which preferably consists of a locking disk 133 arranged on the outer side of the operating arm 128 65 and provided with an annular row of openings 134, and a spring pressed catch 135 arranged on the handle of the crank arm 132 and adapted to engage with one or another of the openings 134. By this means the 70 turning roller may be easily shifted into any desired position and then positively held in place so that the same will operate positively for imparting the proper curvature to the sheet of metal in the formation of a tube 75 therefrom.

It has been found in practice that it is desirable to impart an initial bend in the front 80 part or end portion of the sheet of metal and thus give the sheet a permanent set in order to ensure bringing the longitudinal edges of the tube into a proper overlapping position when the rolling operation has been completed. For this purpose a lifting bar 136 is arranged transversely in a slot 137 in the 85 feed table immediately in rear of the feeding rollers. This bar is lowered so that its upper side is flush with the top of the table when the sheet is placed upon the table and between the feeding rollers and with its front 90 end resting upon the turning roller, as shown in Fig. 9. Thereafter the lifting bar is raised slightly so as to lift that portion of the sheet of metal in rear of the feeding rollers, as 95 shown in Fig. 10, whereby an initial bend is produced in the sheet of metal which gives it a definite and permanent set in the direction in which the same is to be curved for 100 converting the same into a tube. Thereafter the lifting bar is again lowered flush with the upper side of the feed table and then the sheet of metal is fed forwardly between the feeding roller and against the turning roller which causes successive parts of the sheet to 105 be curved in the proper direction for causing the advancing end of the sheet to overlap the trailing end thereof and form a complete tube in which the longitudinal edges thereof overlap each other, as shown by dotted 110 lines in Fig. 9 and by full lines in Fig. 20. Vertical movement may be imparted to the lifting bar 136 by any suitable means, but 115 preferably by the means which are shown in the drawings and which are constructed as follows:

120 138 represents a horizontal lifting shaft which is journaled transversely in suitable bearings on the main frame in rear of the lifting bar and provided with forwardly projecting lifting arms 139 which are connected by means of upright links 140 with the underside of the lifting bar adjacent to 125 opposite ends thereof. The upward move-

ment of the lifting bar is produced by means of a handle 141 connected with one end of the rock shaft 138 outside of the main frame and the downward or return movement of the lifting bar is effected by means of a spring 142 connected at its lower end with the main frame while its upper end is connected with a return arm 143 projecting forwardly from the central part of the lifting shaft 139. The lifting bar 136 is guided in its vertical movements by means of two guide arms 144 projecting downwardly from the underside thereof and each provided at its lower end with a vertical slot 145 which receives a guide rod 146 arranged horizontally and transversely on the adjacent part of the main frame. As the lifting bar 136 rises and falls, the same is compelled to move in a vertical direction and prevented from tilting by engagement of its guide arms 144 with the guide rod 146.

In order to permit the operator to remain constantly at one side of the machine while operating the same during the bending of sheets of metal into tubular form the clutch 84 is operated by means of a handle 147 which is arranged on the same side of the machine as the handles 95 and 105 of the clamping yoke, this clutch operating lever being pivoted at its lower end by means of a pin 148 to the lower end of the main frame and connected by means of a rod 149 with the lower arm of the clutch lever 85, as shown in Figs. 1, 2 and 4.

As a whole, this machine is very efficient and durable in construction and permits of expeditiously bending sheet metal into tubular form with a minimum expenditure of labor and power and thus reducing the cost of manufacturing such articles accordingly.

I claim as my invention:

1. A machine of the character described, comprising a support for the sheet to be bent, upper and lower feeding rollers which receive said sheet from said support, bearings in which opposite ends of the lower roller are journaled, a vertically swinging bearing in which one end of the upper roller is journaled, a divided bearing in which the other end of said upper roller is journaled, said divided bearing having a fixed lower section and a movable upper section, a laterally swinging yoke, a clamping mechanism whereby said yoke is operatively connected with said upper bearing section and which operates to press said upper bearing section down upon said upper feeding roller, and means for turning the sheet as the same issues from said feeding rollers.

2. A machine of the character described, comprising a support for the sheet to be bent, upper and lower feeding rollers which receive said sheet from said support, bearings in which opposite ends of the lower roller are journaled, a vertically swinging bearing in which one end of the upper roller is journaled, a divided bearing in which the other

er is journaled, a divided bearing in which the other end of said upper roller is journaled, said divided bearing having a fixed lower section and a movable upper section, a laterally swinging yoke, a clamping mechanism whereby said yoke is operatively connected with said upper bearing section and which operates to press said upper bearing section down upon said upper feeding roller, and means for turning the sheet as the same issues from said feeding rollers.

3. A machine of the character described, comprising a support for the sheet to be bent, upper and lower feeding rollers which receive said sheet from said support, bearings in which opposite ends of the lower roller are journaled, a vertically swinging bearing in which one end of the upper roller is journaled, a divided bearing in which the other end of said upper roller is journaled, said divided bearing having a fixed lower section and a movable upper section, a laterally swinging yoke, an eccentric loop arranged on said upper bearing section, an eccentric engaging with said eccentric loop, a shaft carrying said eccentric and journaled on said yoke, a clamping mechanism whereby said yoke is operatively connected with said upper bearing section and which operates to press said upper bearing section down upon said upper feeding roller, and means for turning the sheet as the same issues from said feeding rollers.

4. A machine of the character described, comprising a support for the sheet to be bent, upper and lower feeding rollers which receive said sheet from said support, bearings in which opposite ends of the lower roller are journaled, a vertically swinging bearing in which one end of the upper roller is journaled, a divided bearing in which the other end of said upper roller is journaled, said divided bearing having a fixed lower section and a movable upper section, a laterally swinging yoke, an eccentric loop arranged on said upper bearing section, an eccentric engaging with said eccentric loop, a shaft carrying said eccentric and journaled on said yoke, a handle arranged on said shaft, a clamping mechanism whereby said yoke is operatively connected with said upper bearing section and which operates to press said upper bearing section down upon said upper feeding roller, and means for turning the sheet as the same issues from said feeding rollers.

5. A machine of the character described, comprising a support for the sheet to be bent, upper and lower feeding rollers which receive said sheet from said support, bearings in which opposite ends of the lower roller are journaled, a vertically swinging bearing in which one end of the upper roller is journaled, a divided bearing in which the other

end of said upper roller is journaled, said divided bearing having a fixed lower section and a movable upper section, a laterally swinging yoke, an eccentric loop arranged on said upper bearing section, an eccentric engaging with said eccentric loop, a shaft carrying said eccentric and journaled on said yoke, means for yieldingly holding said shaft against turning, a clamping mechanism whereby said yoke is operatively connected with said upper bearing section and which operates to press said upper bearing section down upon said upper feeding roller, and means for turning the sheet as the same issues from said feeding rollers.

6. A machine of the character described, comprising a support for the sheet to be bent, upper and lower feeding rollers which receive said sheet from said support, bearings in which opposite ends of the lower roller are journaled, a vertically swinging bearing in which one end of the upper roller is journaled, a divided bearing in which the other end of said upper roller is journaled, said divided bearing having a fixed lower section and a movable upper section, a laterally swinging yoke, an eccentric loop arranged on said upper bearing section, an eccentric engaging with said eccentric loop, a shaft carrying said eccentric and journaled on said yoke, a handle connected with said shaft, a detent disk arranged on said handle and provided with a plurality of recesses, a spring pressed catch arranged on said yoke and adapted to engage with one or another of said recesses, a clamping mechanism whereby said yoke is operatively connected with said upper bearing section and which operates to press said upper bearing section down upon said upper feeding roller, and means for turning the sheet as the same issues from said feeding rollers.

7. A machine of the character described, comprising a main frame, a support on said frame for the sheet to be bent, upper and lower feeding rollers which receive said sheet from said support, standards arranged on the main frame and provided at their upper ends with bearings in which opposite ends of said lower roller are journaled, a vertically swinging yoke pivoted on one of said standards and provided with a bearing in which one end of said upper roller is journaled, a divided bearing in which the other end of said upper roller is journaled and which has a lower fixed section mounted on the other standard and an upper movable section which is movable toward and from said lower section, a swinging yoke which carries said upper bearing section, and which has a wedging engagement with the standard on the corresponding side of the machine in the normal position of the parts, and means for turning said sheet as the same issues from said rollers.

8. A machine of the character described, comprising a main frame, a support on said frame for the sheet to be bent, upper and lower feeding rollers which receive said sheet from said support, standards arranged on the main frame and provided at their upper ends with bearings in which opposite ends of said lower roller are journaled, a vertically swinging yoke pivoted on one of said standards and provided with a bearing in which one end of said upper roller is journaled, a divided bearing in which the other end of said upper roller is journaled and which has a lower fixed section mounted on the other standard and an upper movable section which is movable toward and from said lower section, a swinging yoke which carries said upper bearing section, yielding detent means for coupling said last mentioned standard and yoke in the normal position of the parts, and means for turning said sheet as the same issues from said rollers.

9. A machine of the character described, comprising a main frame, a support on said frame for the sheet to be bent, upper and lower feeding rollers which receive said sheet from said support, standards arranged on the main frame and provided at their upper ends with bearings in which opposite ends of said lower roller are journaled, a vertically swinging yoke pivoted on one of said standards and provided with a bearing in which the end of said upper roller is journaled, a divided bearing in which the other end of said upper roller is journaled and which has a lower fixed section mounted on the other standard and an upper movable section which is movable toward and from said lower section, a swinging yoke which carries said upper bearing section, yielding detent means for coupling said last mentioned standard and yoke in the normal position of the parts comprising a recess in said last mentioned yoke and a spring pressed catch on said last mentioned standard and engaging with said recess, and means for turning said sheet as the same issues from said rollers.

10. A machine of the character described, comprising a main frame, a support on said frame for the sheet to be bent, upper and lower feeding rollers which receive said sheet from said support, standards arranged on the main frame and provided at their upper ends with bearings in which opposite ends of said lower roller are journaled, a vertically swinging yoke pivoted on one of said standards and provided with a bearing in which one end of said upper roller is journaled, a divided bearing in which the other end of said upper roller is journaled and which has a lower fixed section mounted on the other standard and an upper movable section which is movable toward and from

- said lower section, a vertically swinging yoke having two side bars which are arranged on opposite sides of the adjacent standard which carries the fixed bearing 65 section and have their lower ends pivoted thereto while their upper ends carry between them said movable bearing section, and means for turning said sheet as the same emerges from said feed rollers.
- 10 11. A machine of the character described comprising a main frame, a support on said frame for the sheet to be bent, upper and lower feeding rollers which receive said sheet from said support, standards arranged 70 on the main frame and provided at their upper ends with bearings in which opposite ends of said lower roller are journaled, a vertically swinging yoke pivoted on one of said standards and provided with a bearing 75 in which one end of said upper roller is journaled, a divided bearing in which the other end of said upper roller is journaled and which has a lower fixed section mounted on the other standard and an upper movable section which is movable toward and from 80 said lower section, a vertically swinging yoke having two side bars which are arranged on opposite sides of the adjacent standard which carries the fixed bearing 85 section and have their lower ends pivoted thereto while their upper ends carry between them said movable bearing section, means for wedgingly engaging said last mentioned yoke with the adjacent standard, a detent device which yieldingly connects one of said bars with the adjacent standard, and means for turning said sheet as the same emerges from said feed rollers. 90
- 15 12. A machine of the character described, comprising a main frame, a support on 95 said frame for the sheet to be bent, upper and lower feeding rollers which receive said sheet from said support, standards arranged on the main frame and provided at their upper ends with bearings in which opposite 100 ends of said lower roller are journaled, a vertically swinging bearing in which one end of the upper shaft is journaled, a divided bearing in which the other end of said upper shaft is journaled and which has a fixed lower section and a movable upper section, a swinging yoke which 105 carries said upper bearing section, and connecting means between said swinging bearing and said yoke whereby movement of the latter is transmitted to said upper roller. 110
- 20 13. A machine of the character described, comprising a main frame, a support on said frame for the sheet to be bent, upper and lower feeding rollers which receive said sheet from said support, standards arranged 115 on the main frame and provided at their upper ends with bearings in which opposite ends of said lower roller are journaled, a vertically swinging yoke pivoted on one of said standards and provided with a bearing 120 in which one end of said upper roller is journaled, a divided bearing in which the other end of said upper roller is journaled and which has a lower fixed section mounted on the other standard and an upper movable section which is movable toward and from 125 said lower section, a vertically swinging yoke having two side bars which are arranged on opposite sides of the adjacent standard which carries the fixed bearing section and have their lower ends pivoted thereto while their upper ends carry between them said movable bearing section, means for wedgingly engaging said last mentioned yoke with the adjacent standard, a detent device which yieldingly connects one of said bars with the adjacent standard, and means for turning said sheet as the same emerges from said feed rollers.
- 25 14. A machine of the character described, comprising upper and lower feeding rollers which receive between them the sheet to be bent, means for turning the sheet as the same issues from said rollers, normally fixed bearings in which said lower roller is journaled, a vertically swinging bearing in which one end of the upper shaft is journaled, a divided bearing in which the other end of said upper shaft is journaled and which has a fixed lower section and a movable upper section, a swinging yoke which carries said upper bearing section, and connecting means between said swinging bearing and said yoke whereby movement of the latter is transmitted to said upper roller. 130
- 30 15. A machine of the character described, comprising upper and lower feeding rollers which receive between them the sheet to be bent, means for turning the sheet as the same issues from said rollers, normally fixed bearings in which said lower roller is journaled, a vertically swinging bearing in which one end of the upper shaft is journaled, a divided bearing in which the other end of said upper shaft is journaled and which has a fixed lower section and a movable upper section, a swinging yoke which carries said upper bearing section, and connecting means between said swinging bearing and said yoke whereby movement of the latter is transmitted to said upper roller comprising an arm projecting downwardly from said swinging bearing, and a link connecting said arm with said yoke. 135

16. A machine of the character described, comprising upper and lower feeding rollers which receive between them the sheet to be bent, means for turning the sheet as the same issues from said rollers, normally fixed bearings in which said lower roller is journaled, a vertically swinging bearing in which one end of the upper shaft is journaled, a divided bearing in which the other end of said upper shaft is journaled and which has a fixed lower section and a movable upper section, a swinging yoke which carries said upper bearing section, and connecting means between said swinging bearing and said yoke whereby movement of the latter is transmitted to said upper roller comprising an arm projecting downwardly from said swinging bearing, and a link pivotally connected at one end with said yoke while its opposite end has a slack connection with said arm.

17. A machine of the character described, comprising upper and lower feeding rollers adapted to receive between them the sheet to be bent, a turning roller arranged on the outlet side of said feeding rollers and adapted to intercept said sheet and turn it to one side, and means for adjusting said turning roller in a direction transversely of the path of the sheet as it issues from said feeding rollers comprising a cross bar on which said turning roller is pivotally mounted, a curved arm connected with said cross bar, and a curved guide which receives said curved arm.

18. A machine of the character described, comprising upper and lower feeding rollers adapted to receive between them the sheet to be bent, a turning roller arranged on the outlet side of said feeding rollers and adapted to intercept said sheet and turn it to one side, and means for adjusting said turning roller in a direction transversely of the path of the sheet as it issues from said feeding rollers comprising a cross bar on which said turning roller is pivotally mounted, a curved arm connected with said cross bar, a curved guide which receives said curved arm, and a clamping screw on said guide passing through a slot in said curved arm.

19. A machine of the character described comprising upper and lower feeding rollers adapted to receive between them the sheet to be bent, a turning roller arranged on the outlet side of said feeding rollers and adapted to intercept said sheet and turn it to one side, and means for adjusting said turning roller in a direction transversely of the path of the sheet as it issues from said feeding rollers comprising a cross bar on which said turning roller is pivotally mounted, a curved arm connected with said cross bar, a curved guide which receives said

curved arm, and an adjusting screw arranged in said curved arm and engaging with a stationary abutment.

20. A machine of the character described, comprising upper and lower feeding rollers adapted to receive between them the sheet to be bent, a turning roller arranged on the outlet side of said feeding rollers and adapted to intercept said sheet and turn it to one side, and means for adjusting said turning roller in a direction transversely of the path of the sheet as it issues from said feeding rollers comprising a cross bar on which said turning roller is pivotally mounted, a curved arm connected with said cross bar, a curved guide which receives said curved arm, a clamping screw arranged on said guide and passing through a slot in said curved arm, and an adjusting screw arranged on said curved arm and engaging a fixed abutment.

21. A machine of the character described comprising upper and lower feeding rollers adapted to receive between them the sheet to be bent, a turning roller arranged on the outlet side of said feeding rollers and adapted to intercept said sheet and turn it to one side, and means for adjusting said turning roller in a direction transversely of the path of the sheet as it issues from said feeding rollers comprising a cross bar on which said turning roller is pivotally mounted, a rock arm which carries said cross bar, a rocking eccentric, and a shifting rod connected at one end with said cross bar and provided at its other end with a strap surrounding said eccentric.

22. A machine of the character described, comprising upper and lower feeding rollers adapted to receive between them the sheet to be bent, a turning roller arranged on the outlet side of said feeding rollers and adapted to intercept said sheet and turn it to one side, and means for adjusting said turning roller in a direction transversely of the path of the sheet as it issues from said feeding rollers comprising a cross bar on which said turning roller is pivotally mounted, a rock arm which carries said cross bar, a rocking eccentric, a shifting rod connected at one end with said cross bar and provided at its other end with a strap surrounding said eccentric, a rocking adjusting arm connected with said eccentric, and means for shifting said rock arm.

23. A machine of the character described, comprising upper and lower feeding rollers adapted to receive between them the sheet to be bent, a turning roller arranged on the outlet side of said feeding rollers and adapted to intercept said sheet and turn it to one side, and means for adjusting said turning roller in a direction transversely of the path of the sheet as it issues from said

feeding rollers comprising a cross bar on which said turning roller is pivotally mounted, a rock arm which carries said cross bar, a rocking eccentric, a shifting rod connected at one end with said cross bar and provided at its other end with a strap surrounding said eccentric, a rocking adjusting arm connected with said eccentric, and means for shifting said rock arm comprising a gear pinion pivotally mounted on the outer end of said adjusting arm, and a stationary gear segment with which said pinion meshes.

24. A machine of the character described, comprising upper and lower feeding rollers adapted to receive between them the sheet to be bent, a turning roller arranged on the outlet side of said feeding rollers and adapted to intercept said sheet and turn it to one side, and means for adjusting said turning roller in a direction transversely of the path of the sheet as it issues from said feeding rollers comprising a cross bar on which said turning roller is pivotally mounted, a rock arm which carries said cross bar, a rocking eccentric, a shifting rod connected at one end with said cross bar and provided at its other end with a strap surrounding said eccentric, a rocking adjusting arm connected with said eccentric, and means for shifting said rock arm comprising a gear pinion pivotally mounted on the outer end of said adjusting arm, a stationary gear segment with which said pinion meshes, a rotary handle connected with said pinion, and means for locking said handle in different circumferential positions.

25. A machine of the character described comprising upper and lower feeding rollers adapted to receive between them the sheet to be bent, a turning roller arranged on the outlet side of said feeding rollers and adapted to intercept said sheet and turn it to one side, and means for adjusting said turning roller in a direction transversely of the path of the sheet as it issues from said feeding rollers comprising a cross bar on which said turning roller is pivotally mounted, a rock arm which carries said cross bar, a rocking eccentric, a shifting rod connected at one end with said cross bar and provided at its other end with a strap surrounding said eccentric, a rocking adjusting arm connected with said eccentric, and means for shifting said rock arm comprising a gear pinion pivotally mounted on the outer end of said adjusting arm, a stationary gear segment with which said pinion meshes, a rotary handle connected with said pinion, and means for locking said handle in different circumferential positions comprising a locking disk arranged on said adjusting arm and provided with an annular row of openings arranged concentrically with said gear pinion, and a catch movably mounted on

said handle and adapted to engage with one or another of said openings.

26. A machine of the character described, comprising upper and lower feeding rollers which are adapted to receive between them the sheet to be bent, means for turning the sheet as the same issues from the front side of the rollers, and means for producing an initial upward bend in the sheet in rear of the feeding rollers.

27. A machine of the character described, comprising upper and lower feeding rollers which are adapted to receive between them the sheet to be bent, means for turning the sheet as the same issues from the front side of the rollers, and means for producing an initial upward bend in the sheet in rear of the feeding rollers comprising a vertically movable lifting bar normally arranged below the path of the sheet and means for raising said bar.

28. A machine of the character described comprising upper and lower feeding rollers which are adapted to receive between them the sheet to be bent, means for turning the sheet as the same issues from the front side of the rollers, and means for producing an initial upward bend in the sheet in rear of the feeding rollers comprising a vertically movable lifting bar normally arranged below the path of the sheet, means for raising said bar comprising a rock shaft, arms on said rock shaft, and links connecting said rock arms with said lifting bar.

29. A machine of the character described, comprising upper and lower feeding rollers which are adapted to receive between them the sheet to be bent, means for turning the sheet as the same issues from the front side of the rollers, and means for producing an initial upward bend in the sheet in rear of the feeding rollers comprising a vertically movable lifting bar normally arranged below the path of the sheet, means for raising said bar comprising a rock shaft, arms on said rock shaft, links connecting said rock arms with said lifting bar, a hand lever connected with said shaft for raising said bar, and means for depressing said bar consisting of a return arm connected with said shaft, and a spring connecting said return arm with a stationary part.

30. A machine of the character described, comprising upper and lower feeding rollers which are adapted to receive between them the sheet to be bent, means for turning the sheet as the same issues from the front side of the rollers, and means for producing an initial upward bend in the sheet in rear of the feeding rollers comprising a vertically movable lifting bar normally arranged below the path of the sheet, means for raising said bar and means for guiding said bar.

31. A machine of the character described comprising upper and lower feeding rollers

which are adapted to receive between them the sheet to be bent, means for turning the sheet as the same issues from the front side of the rollers, and means for producing an initial upward bend in the sheet in rear of the feeding rollers comprising a vertically movable lifting bar normally arranged be-

low the path of the sheet, means for raising said bar, means for guiding said bar comprising a stationary guide bar, and guide arms secured to the underside of said lifting bar and provided with slots which receive said guide rod.

BROR J. LINDGREN.
